[57] CLAIM

The ornamental design for a web drying section, as shown and described.

DESCRIPTION

FIG. 1 is a side elevational view of a web drying section, showing our new design;

FIG. 2 is a bottom plan view thereof;

FIG. 3 is a top plan view thereof;

FIG. 4 is a side elevational view of a second embodiment;

FIG. 5 is a top plan view thereof;

FIG. 6 is a bottom plan view thereof;

FIG. 7 is an end elevational view of FIG. 1;

FIG. 8 is the opposite end elevational view;

FIG. 9 is the opposite side view of FIG. 1;

FIG. 10 is a perspective view of FIG. 1;

FIG. 11 is an end elevational view of FIG. 4;

FIG. 12 is the opposite end elevational view thereof;

FIG. 13 is the opposite side elevational view of FIG. 4; and

FIG. 14 is a perspective view thereof.
